The ornamental design for an iconic support for a storage bin, as shown and described.

DESCRIPTION

In a preferred embodiment, the nature of this product is an iconic support for a storage bin that is located above a work-surface such as a desk.

FIG. 1 is a front, left, upper perspective view of an iconic support for a storage bin embodying our new design;

FIG. 2 is a left side elevational view thereof, the right side elevational view being identical;

FIG. 3 is a front elevational view thereof, the rear elevational view being a mirror image thereof;

FIG. 4 is a top plan view thereof; and,

FIG. 5 is a bottom plan view thereof.

The broken lines in the drawings are for illustrative purposes only and form no part of the claimed design.
